UNITED STATES PATENT OFFICE.

PHILIP A. FISCHER, OF NEW YORK, N. Y.

DRINKING-CUP.

1,373,182.

Specification of Letters Patent. Patented Mar. 29, 1921.

Application filed November 22, 1920. Serial No. 425,613.

To all whom it may concern:

Be it known that I, PHILIP A. FISCHER, a citizen of the United States, residing at No. 409 Edgecomb avenue, in the county of 5 New York, State of New York, have invented certain new and useful Improvements in Drinking-Cups; and I do hereby declare the following to be a full, clear, and exact description of the invention, such as 10 will enable others skilled in the art to which it appertains to make and use the same.

This invention relates to drinking cups which are ordinarily made of paper, of the type which may be folded flat for shipment 15 and which are caused to open by pressure of the fingers against the edges of the cup.

A paper cup according to this invention is provided with a pouring funnel or mouthpiece at the top, the discharge opening of 20 which is in the middle of the top of the cup. The discharge opening, moreover, is elongated in a horizontal direction, so that when a cup is in use, this opening may readily fit 25 into the mouth of the user. It has heretofore been proposed to provide a folding drinking cup with a funnel at one corner, the discharge opening of which is elongated vertically. It is evident that the use of a 30 cup with such a vertical opening is very awkward as compared with one with a horizontally arranged mouthpiece.

The use of a funnel at the top of the cup provides a mouth piece which is convenient for the ordinary user and is particularly 35 convenient for feeding children and invalids, where the cup needs to be held by some one other than the person drinking.

The funnel is formed by a pair of co-operating flaps carried by one of the body 40 portions, which are folded inwardly along diagonal lines converging toward the top of the cup. These diagonal lines are so located that the upper outer corners of the other body portion are folded inwardly with the 45 flaps when the cup is flat. These inwardly folded corners are under a slight strain due to the folding, and act as elastic hinges; when the cups are unpacked these hinges tend to spring outwardly a small amount 50 and therefore open the cup slightly. This is particularly advantageous because once the cup is thus preliminarily opened, the pressure of the fingers along the edges of the cup will readily open it completely.

In order to still further facilitate the 55 opening of the cup either the funnel, which

is carried by the back body portion of the cup, or the front body portion of the cup, may be provided with a finger tab which is pulled outwardly when it is desired to open 60 the cup.

The funnel portion or mouthpiece of the cup is so made that when the cup is folded the lower edges of the funnel overlap the upper edges of the front body portion of 65 the cup, so that none of the interior of the cup is exposed to dust and dirt or to contact with the fingers. In this instance also, either the funnel portion or the front body portion is provided with a finger tab for 70 opening the cup.

In the manufacture of the cup, one of the body portions may be made narrower than the other, a construction which tends to cause the wider body portion to bulge outwardly a small amount. This starts the 75 opening of the cup, and the pressure of the fingers against the vertical edges of the cup will cause it to open completely. This construction co-operates with the above mentioned folded-in corners to cause a preliminary opening of the cup, the opening being carried to completion by pressure against the edges of the cup; there is no necessity of inserting the fingers in the cup at all, 85 which is necessary with some types of paper cups and which is obviously an unsanitary procedure.

For a clearer understanding of the invention, attention is called to the accompanying drawings illustrating two embodiments 90 of the invention. It should be understood, however, that the essential features of the invention may be carried out in other ways than in the particular forms here shown.

In these drawings, Figure 1 is a perspective view of a complete cup; Fig. 2 is a side view of the same; Fig. 3 is a sectional view on the line 3—3 of Fig. 1; Fig. 4 is a sectional view on the line 4—4 of Fig. 1, looking in the direction of the arrows; Fig. 5 shows a blank from which the cup is made; Fig. 6 shows a partially completed cup, before the funnel forming flaps are folded in; Fig. 7 is a front view of a modified form; 100 Figs. 8 and 9 are sectional views taken on the lines 8—8 and 9—9, respectively, of Fig. 7 looking in the direction of the arrows; Fig. 10 is a sectional view of the open cup; and Fig. 11 is a view of a blank from which 110 the modified form is made.

Referring now to Figs. 1 to 6, the cup is

- formed of a back portion 5 provided with side flaps 6 and 7 and the bottom flap 8 integral therewith. The flaps 6, 7 and 8 are folded together as shown in Fig. 6 to form 5 a front body portion indicated generally at 9, which with the back portion 5 forms the body of the cup. The side flaps are folded in along the lines 10, while the bottom flap is folded along the lines 11.
- 10 The upper part of the back portion 5 of the cup is provided with a pair of flaps indicated at 12 and 13. One of the flaps is provided with adhesive 14, while the other is provided with a finger tab 15. After the 15 side and bottom flaps are folded as shown in Fig. 6, the two flaps 12 and 13 are folded inwardly along the diagonal lines 16 and 17 which converge toward the top of the cup. These diagonals 16 and 17 intersect 20 the folded lines 10 at points a short distance below the top edges of the side flaps 6 and 7. When, therefore, the flaps 12 and 13 are folded along said diagonals the upper corners 18 of the flaps 6 and 7 will be folded 25 over on the front face 9 of the cup. These corners are under more or less strain due to being folded in, but are held folded when the cups are packed flat for shipment or are packed in the usual dispensing cabinet.
- 30 When removed from the cabinet, however, the folded corners act like spring hinges and tend to spring outwardly and return to their original position, a movement which pushes the edges of the flaps 12 and 13 outwardly, 35 and so tends to open the cup a small amount. This is a useful feature of the invention because it is well known that if a paper cup is opened a little, pressure against the edges of the cup will readily open it completely.
- 40 When the flaps 12 and 13 are folded along the diagonals 16 and 17 and are pasted together, a finished cup, as shown in Figs. 1 and 2, is obtained. The cup is filled in much the usual way through the filling opening 45 A, which is clearly shown just below the tab 15. The upper part of the back portion 5 of the cup co-operates with the two flaps in forming a funnel or mouthpiece 21, the pouring channel of which is inclosed all the 50 way up to the discharge opening. The upper part of the back portion of the cup terminates in a comparatively short horizontal edge 19 which co-operates with the edges 20 of the flaps 12 and 13 to form a horizontally 55 extending elongated discharge opening 22, the plane of which is substantially perpendicular to the plane of the cup. This opening 22 is evidently of convenient form to drink from. The tab 15 is used to prelimi- 60 narily open the cup, after which a pressure against the vertical edges of the cup opens it completely. It is apparent as the tab 15 is lifted, the front body portion 9 of the cup will be likewise lifted due to the connection 65 of these parts by the folded corners 18.

Referring to Fig. 4, a construction is shown in which one of the body portions, such as 5, is made slightly narrower than the other body portion 9. This causes the body portion 9 to bulge a small amount, 70 thus opening the cup slightly. As has been stated, when once the cup is slightly opened it may be completely opened by pressure against the sides of the cup. This feature co-operates with the folded corners to cause 75 a preliminary opening of the cup without the necessity of inserting the fingers.

Referring now to Figs. 7 to 11, the cup there shown is similar in several particulars to the cup already described and the corresponding parts are similarly numbered. The pouring funnel or mouthpiece, indicated at 21, has its lower edges 24 which are the same as the edges 24 of the flaps 12 and 13, overlapping the upper edges 25 of the side 80 flaps 6 and 7. This completes the covering 85 of the interior of the cup and protects it from dust and dirt so that it comes to the user in a thoroughly sanitary condition. In this cup also either the lower edges of the 90 pouring funnel may be provided with a finger tab similar to the tab 15 shown in Fig. 1, or the front body portion may be provided with an opening tab, as indicated at 26. Due to the fact that the lower edges 95 of the funnel overlap the upper edges of the front portion 9 and so overlap the tab, the tab is bent backwardly, as shown in Fig. 9. A lifting of such tab will evidently lift the front portion 9 of the cup, and will lift the 100 front portion of the funnel due to the connecting corners 18. This type of cup may also be constructed with a bulging section, as shown in Fig. 4.

The important features of the invention 105 may be briefly summarized as follows: The provision of a pouring funnel or mouthpiece, the discharge opening of which is horizontally arranged and is at the middle 110 of the top portion of the cup; the provision of the folded-in corners 18 of the front portion which act as elastic hinges to preliminarily open the cup; the provision of finger tabs on either the funnel or the front body portion for opening the cup; the overlapping 115 of the upper edges of the front body portion of the cup by the lower edges of the funnel so as to prevent access of dust and dirt to the interior of the cup; and the making of one of the body portions of the 120 cup narrower than the other which tends to make the broader portion bulge outwardly. It should be understood that these features of the invention may be embodied in other types of cups than is here specifically illustrated, and that it is not necessary to use 125 every feature of the invention in a particular cup.

I claim as my invention:—

1. A folding drinking cup provided with 130

5 a filling opening and with a pouring funnel, the discharge opening of the funnel being elongated horizontally, the plane of said discharge opening, when in pouring position, being substantially perpendicular to the plane of the cup.

10 2. A folding drinking cup provided with a filling opening and with a pouring funnel, the discharge opening of the funnel being elongated horizontally, the pouring channel of the funnel being inclosed up to said discharge opening.

15 3. A folding drinking cup provided with a pouring funnel, the discharge opening of which is elongated horizontally, part of the edge of the funnel at the larger end thereof being movable away from the cup for permitting filling of the cup.

20 4. A folding drinking cup provided with a filling opening, and a pouring funnel carried by the cup adjacent said filling opening, the discharge opening of the pouring funnel being located centrally of the cup and elongated horizontally.

25 5. A folding drinking cup provided with a filling opening and a funnel or mouthpiece adjacent said filling opening, the funnel being tapered upwardly and terminating in an elongated pouring or discharge opening which is horizontally disposed and is elongated in the plane of the cup.

30 6. A foldable drinking cup provided with a filling opening and with a top portion forming a pouring funnel adjacent said filling opening, the funnel being formed of an extension of one side of the cup and a pair of coöperating flaps carried thereby, the discharge opening of the funnel being in the middle of the top of the cup.

35 7. A foldable drinking cup provided with a filling opening and comprising front and back body portions, the back portion including as a part thereof a pouring funnel located adjacent said filling opening, and 40 a tab for facilitating the opening of the cup, carried by one of the said body portions.

45 8. A foldable drinking cup provided with a filling opening and comprising front and back body portions, the back portion be-

ing provided with a pouring funnel adjacent said filling opening the discharge opening of the funnel being in the middle of the top of the cup, and a tab for facilitating the opening of the cup, carried by the 55 lower edge of the pouring funnel.

9. A foldable drinking cup provided with a filling opening and comprising front and back body portions, the back portion being provided with a pouring funnel, adjacent said filling opening, part of the lower edge of the funnel being movable away from and arranged to overlap the upper edge of the front body portion when the cup is folded.

10. A foldable drinking cup provided with a filling opening and comprising front and back body portions, the back portion including as a part thereof a pouring funnel, adjacent said filling opening, part of the lower edge of the funnel being movable away from and arranged to overlap the upper edge of the front body portion when the cup is folded, and a tab for facilitating the opening of the cup carried by one of 75 said body portions.

11. A foldable drinking cup, provided with front and back body portions, the back body portion being provided with coöperating flaps which are folded inwardly to form a pouring funnel at the top of the cup, the line of fold being such as to cause an inward folding of the upper outer corners of the front body portion.

12. A foldable drinking cup, provided with front and back body portions, the back body portion being provided with flaps which are folded along diagonal lines converging toward the top of the cup to form a pouring funnel or mouthpiece, the said diagonal lines of fold crossing the upper outer corners of the front body portion, the folded-in corners of the front portion tending to spring outwardly to preliminarily open the cup and also serving to move the lower edge of the pouring funnel outwardly when the edges of the cup are pressed together.

In testimony whereof I affix my signature.
PHILIP A. FISCHER.
